UNITED STATES PATENT OFFICE

CARL F. GRAESSER, OF SPRINGFIELD, MASSACHUSETTS, ASSIGNOR TO AMERICAN BOSCH CORPORATION, OF SPRINGFIELD, MASSACHUSETTS, A CORPORATION OF NEW YORK

DESIGN FOR A RADIOCABINET

Application filed February 24, 1932. Serial No. 42,976. Term of patent 3½ years.

To all whom it may concern:

Be it known that I, CARL F. GRAESSER, a citizen of the United States, residing at Springfield, in the county of Hampden and State of Massachusetts, have invented a new, original, and ornamental Design for Radio Cabinets, of which the following is a specification, reference being had to the accompanying drawing, forming part thereof.

The figure is a perspective view of a radio cabinet showing my new design.

I claim:

The ornamental design for a radio cabinet, as shown.

CARL F. GRAESSER.
